UNITED STATES PATENT OFFICE

EMILE PIRON, OF NEW YORK, N. Y.

OVEN-HEATING SYSTEM.

1,806,023.

Specification of Letters Patent. Patented June 10, 1919.

Application filed July 20, 1918. Serial No. 245,909.

To all whom it may concern:

Be it known that I, EMILE PIRON, a subject of the King of Belgium, residing at New York city, in the county of New York, State of New York, have invented certain new and useful Improvements in Oven-Heating Systems.

The present invention relates to improvements in heating arrangements for ovens or other receptacles in which materials to be heated are placed, such as coke ovens, kilns or the like.

One of the objects of my invention is to provide a heating system that will be of the continuous regenerating type and which will be very efficient and at the same time, simple in construction.

Another object of my invention is to provide a heating system in which all of the passages will be relatively direct and accessible and the walls subjected to a minimum of the inequality of heating which is the cause of destruction of the walls in ovens as usually constructed.

With these and other objects in view my invention consists of the novel arrangement of parts herein described and pointed out in the appended claims.

In the drawings, Figure 1 is a horizontal cross-section through a portion of a battery of coke ovens, which I have adopted for purpose of illustration, the section being taken on the line 1—1 of Fig. 2.

Fig. 2 is a vertical cross-section of a portion of the battery taken on the line 2—2 of Fig. 4.

Fig. 3 is a vertical cross-section taken on the line 3—3 of Fig. 4.

Fig. 4 is a vertical cross-section taken on the line 4—4 of Fig. 3.

The corresponding parts are referred to both in the drawings and in the specification by similar reference characters.

For purpose of illustration, I have shown a portion of two of a battery of ovens, such as are used in producing coke or the like. The ovens 10 are shown disposed horizontally and are closed at the front by the doors 11. Between the ovens 10 are located a series of vertically disposed combustion chambers 12, at the top of each of which is a burner outlet 13 which communicates through the pipe 14 with any suitable source of supply of fuel, which in this instance is gas.

Below each of the ovens 10 is a series of

vertical waste gas flues 15, each communicating with a common horizontal waste gas flue 16 which will be connected to a chimney or any other suitable device for producing a draft. Between the lower part of each of the combustion chambers 12 and the flues 15 is an outlet 17.

Between each pair of combustion chambers 12 is placed an air duct 18 which, as shown best in Fig. 4, is relatively narrow until it reaches the bottom of the combustion chambers 12, when it expands into a wider portion which communicates at the bottom with a horizontal air inlet duct 19. As shown in Fig. 4, the walls of the air ducts 18 do not connect at the top with the upper portion of the oven walls but are separated therefrom sufficiently to provide communication between the ducts 18 and the heating chamber 12. The wall above them is preferably curved as shown.

In operation, gas is supplied through the openings 14 and ignited in the combustion chambers 12. Air from the outside passes through the air inlet ducts 19 into the air ducts 18 and is mixed with the incoming gas at the burner openings to be burned in the combustion chambers 12. The hot gases from these chambers pass through the openings 17 into the waste gas flues 15 and from thence to the stack through the horizontal flues 16. The heat from the combustion chambers 12 passes through the side walls into the oven space 10 and the air supplied by the air ducts 18 is heated as it passes the walls of the waste gas flues 15, and also between the walls of the combustion chambers 12. This serves as a continuous regeneration, because the temperature of the air is raised as it passes upward from the inlet duct 19 to the burner opening by reason of the heat which it receives from the waste gas flues 15 and also from the combustion chambers 12.

I provide the air ducts 18 between each pair of combustion chambers not only as a ready means for supplying air to the burner, but also to equalize the heating of the walls surrounding each of the combustion chambers 12. If the air ducts 18 were not placed between the combustion chambers, it is obvious that the wall between these chambers would receive and retain much more heat than the walls between the combustion chamber and the oven. The wall between the combustion chamber and the oven is, of

course, kept somewhat cool by reason of the passage of the heat into the oven space, whereas the wall between two combustion chambers of equal temperature has no means by which its temperature may be reduced. By providing the air duct 18, I am able to maintain the walls between the combustion chambers at as low a temperature as the walls between the combustion chambers and the ovens themselves, and thus prevent a rapid destruction of these walls. With the air carried through this space as part of my regeneration system, I also avoid any waste of heat which may escape from the combustion chambers in this cooling of the walls.

In order that a system of continuous regeneration shall be efficient, it is essential that the incoming air shall be in contact for a long time with the wall heated by the waste gases. To this end, I make the waste gas flues high and narrow and vertical and similarly, I make the air ducts vertical and narrow. It will be seen that, by this arrangement, I provide a wall of large area on opposite sides of which the hot waste gases and the incoming air are flowing in opposite directions, so that substantially all of the heat from the waste gases may be transferred to the incoming air.

30 By the arrangement which I have described, I have provided a simple and effective arrangement which can be constructed readily and which avoids the use of complicated arches and brick work and which can be duplicated indefinitely to produce a compact arrangement of a battery of ovens working at high efficiency by continuous regeneration, thus avoiding the reversal of gas and air supply necessary when checkerwork is used to absorb the heat. All complicated and unaccessible passages which are liable to become clogged are avoided and especially all passages for gas which are subjected to heat before the gas is ignited are avoided.

50 By providing the downwardly directed passages between the combustion chambers and the air ducts, I cause the heated air to enter the combustion chamber in a downwardly direction at the mouth of the burner. This causes the gas and the air to be mixed thoroughly as they enter the combustion chamber, thus preventing the formation of soot which is liable to occur if the air is injected into the chamber below the mouth of the burner.

By locating the waste gas flues so that their tops are adjacent the bottom of the oven, I insure the correct heating of that part of the oven so that the coking can proceed at that point at substantially the same rate as in other portions of the oven.

60 It will be understood that while my arrangement is particularly adapted for use with coke ovens, it is by no means limited to such uses. My arrangement may be used for heating any space.

I claim—

1. A horizontal oven, a series of vertical waste gas flues beneath and adjacent the bottom of the oven and extending parallel with the axis thereof, the waste gas flues being relatively high and narrow in cross-section, a series of vertical combustion chambers adjacent the side wall of the oven and communicating at the bottom with the top of the waste gas flues, a burner at the upper end of each combustion chamber, a series of vertical air ducts, each having its upper portion located between a pair of the combustion chambers and its lower portion extending downwardly adjacent the wall of the waste gas flues, each air duct being relatively high and narrow in cross-section and communicating with the upper end of one of the combustion chambers adjacent the burner therein.

2. A horizontal oven, a series of vertical waste gas flues beneath and adjacent the bottom of the oven and extending parallel with the axis thereof, the waste gas flues being relatively high and narrow in cross-section, a series of vertical combustion chambers adjacent the side wall of the oven and communicating at the bottom with the tops of the waste gas flues, a burner at the upper end of each combustion chamber, a series of vertical air ducts, each having its upper portion located between a pair of the combustion chambers and its lower portion extending downwardly adjacent the wall of the waste gas flues, each air duct being relatively high and narrow in cross-section, and communicating passages between the upper end of each air duct and the upper end of one of the combustion chambers, the communicating passages being constructed and arranged to direct the air into the combustion chamber in a downwardly direction from a point not lower than the mouth of the burner.

E. PIRON.
